UNITED STATES PATENT OFFICE.

JOSEPH A. MELOON, OF NEEDHAM, MASSACHUSETTS.

WINDOW ATTACHMENT.

1,405,057.

Specification of Letters Patent. Patented Jan. 31, 1922.

Application filed May 13, 1921. Serial No. 469,170.

To all whom it may concern:

Be it known that I, JOSEPH A. MELOON, a citizen of the United States, residing at Needham, in the county of Norfolk and 5 State of Massachusetts, have invented new and useful Improvements in Window Attachments, of which the following is a specification.

The chief object of this invention is to 10 provide an attachment adapted to be quickly and conveniently secured to and removed from a window casing, and to project inwardly therefrom, and constitute, when the lower sash is raised, a barrier preventing 15 the entrance of rain and snow, a deflector adapted to direct entering air upwardly into a room, and a screen shielding occupants of the room from observation from the outside, so that the usual shade may be left raised 20 for the free admission of air.

Other objects are to provide an attachment of such construction that it may be engaged with simple and inexpensive anchoring fixtures attached to the casing, may be 25 folded into compact form for storage when not in use, and does not interfere with the movements of the lower sash and of the window shade.

To the above-mentioned and other related 30 ends the invention consists in the improvements hereinafter described and claimed.

Of the accompanying drawings forming a part of this specification,—

Figure 1 is a perspective view, showing 35 an attachment embodying the invention in its operative position in a window, the lower sash being raised.

Figure 2 is a vertical section through the attachment and window.

40 Figure 3 is a fragmentary side view, showing portions of the attachment in position for storage.

Figure 4 is a reduced plan view of the flexible sheet hereinafter described.

45 Figure 5 is a section on line 5—5 of Figure 2.

Figure 6 is a section on line 6—6 of Figure 2.

50 Figure 7 is a fragmentary view, showing a modification.

The same reference characters indicate the same parts in all of the figures.

55 My improved attachment includes an elongated resilient strip 12, preferably of spring steel, normally straight and adapted to be flexed into arched form. The end portions of the strip are provided with means for en-

gaging suitable anchoring fixtures attached to the upright members 13 of a window casing, at a considerable height above the sill 14, these being hereinafter referred to as the upper anchoring fixtures. The construction is such that when the end portions of the strip are engaged with said upper fixtures, the strip is supported and confined in arched 65 form, and projects inwardly from the casing, as shown by Figures 1 and 2.

The upper anchoring fixtures are preferably embodied in headed screws 15 and 16, inserted in the upright members 13, with 70 their heads projecting as shown by Figure 5. The end portions of the strip are provided with notches 17 and 18, as shown by Figure 3, the notches 17 being formed to engage the screws 15, while the notches 18 are 75 formed to engage the screws 16. The screws 16 are higher than the screws 15, and the notches 18 are formed respectively in the lower and upper edges of the strip 12, the arrangement being such that the strip may 80 be flexed, held in an inclined position while its ends are being inserted between the screws, and then moved to the horizontal position shown by Figures 1 and 2, to engage the notches with the screws, the arched strip 85 being thus securely confined against any movement excepting a movement which raises its central portion.

The attachment also includes a flexible sheet 20 of any suitable sheet material, preferably cloth, engaged at one edge with the strip 12, and formed to depend therefrom and bear on the sill 14.

Other members of the attachment are stiffening rods 21, hinged to the end portions of 95 the strip, engaged with two opposite edges of the sheet 20, and adapted to detachably engage lower anchoring members on the casing, said rods reinforcing and confining the edges of the sheet with which they are engaged, so that said edges are held in predetermined positions. The lower anchoring members are preferably screw-eyes 23, inserted in the upright casing members 13, and formed to receive the lower end portions of 100 the rods 21, the rods being adapted to slide in the screw-eyes and to rest on the sill 14. The sheet 20 is provided with a pocket 24, receiving the major portion of the strip 12, and with pockets 25, receiving the major portions of the stiffening rods 21, said pockets being formed by turning in edge portions of the sheet and securing the turned-in portions by stitches 26.

The stiffening rods are preferably hinged to the end portions of the strip 12, by means of links 27 pivoted at 28 to the rods, and at 29 to the strip, the arrangement being such that the attachment may be folded as indicated by Figure 3, the rods and the strip being substantially parallel with each other.

I have omitted the sheet 20 from Figure 3, to avoid confusion. The upper edge of 10 the sheet having the pocket 24, is elongated, to cover the major portion of the strip 12, and be arched therewith. The edges having the pockets 25 are inclined and converge from the upper edge, as shown by Figure 4, 15 so that the lower portion of the sheet adjacent to the sill 14, is substantially flat, as indicated by Figure 1. The sheet is extended from the pockets 25, at its lower end to form a flap 28, adapted to rest loosely on the sill, 20 as shown by Figure 2.

In installing the attachment, the strip 12 is flexed, its ends are engaged as described, with the screws 15 and 16, the lower ends of the stiffening rods are inserted in the 25 screw-eyes 23, and the flap 28 is deposited on the sill. The sheet 20 is thus supported to form a barrier excluding rain and snow from the room when the lower sash 30 is opened, and a deflector adapted to guide 30 air upwardly into the room, as indicated by the arrows in Figure 2, the air thus guided being prevented from impinging directly on the occupant of a bed near the window.

The sheet also forms a screen, preventing 35 outsiders from looking through the window below a partially raised shade, so that privacy is secured without lowering the shade to exclude air.

The attachment may be quickly removed 40 by raising the central portion of the strip 12 to disengage the ends thereof from the screws 15 and 16, this operation not only detaching the strip 12 from the screws, but also automatically withdrawing the stiffening 45 rods from the screws-eyes.

The stiffening rods may be hinged directly to the strip 12, as shown by Figure 7, their upper ends being preferably curved to facilitate folding.

50 The screws 15 and 16 may be on the same level, as shown by Figure 7, instead of at different levels, in which case the strip 12 should be of sufficient width to receive relatively deep notches 17 and 18.

55 The flap 28 may be stiffened and weighted to hold it down securely upon the sill 14, as by a strip 28^a of heavy webbing, leather or other suitable material.

The upper edge of the sheet 20 is curved, 60 as shown by Figure 4, to compensate for the curvature imparted to said edge by the operation of arching the strip 12.

The attachment is foldable in a variety of ways into shape for convenient storage 65 when not in use.

I claim:

1. A window attachment for the purposes stated, comprising an elongated resilient strip, having means at its end portions for detachable engagement with upper anchoring fixtures on a window casing, and adapted to be supported thereby in arched form and projecting inwardly from the casing; a flexible sheet engaged at one edge with said strip and formed to depend therefrom and bear on a window sill, and stiffening rods hinged to the end portions of the strip, engaged with two opposite edges of the sheet, and adapted to detachably engage lower anchoring fixtures on the casing. 70

2. A window attachment substantially as specified by claim 1, said sheet having an elongated upper edge, provided with means for engaging said strip, and inclined lateral edges, converging from the upper edge, and 80 provided with means for engaging said stiffening rods.

3. A window attachment substantially as specified by claim 1, said sheet having an elongated upper edge, provided with means 90 for engaging said strip, inclined lateral edges, converging from the upper edge, and provided with means for engaging said stiffening rods, and a loose flap projecting from said inclined edges, and adapted to bear on 95 a window sill.

4. A window attachment substantially as specified in claim 1, said sheet having an elongated upper edge provided with a pocket adapted to receive the major portion 100 of said strip, and inclined lateral edges converging from the upper edge and provided with pockets adapted to receive the major portions of said stiffening rods.

5. A window attachment substantially as 105 specified by claim 1, said stiffening rods being hinged to the end portions of said strip by links pivoted to the rods and to the strip, the arrangement being such that the rods may extend substantially parallel with the 110 strip when the attachment is folded.

6. In combination, a window casing having upper anchoring fixtures embodied in headed screws arranged in pairs, and lower anchoring members embodied in screw-eyes; 115 and an attachment comprising an elongated resilient strip having notches in its end portions, adapted to detachably engage said screws, so that the strip may be supported in arched form projecting inwardly from the casing, a flexible sheet engaged at one edge with said strip and formed to depend therefrom and bear on the sill of said casing, and stiffening rods hinged to the end portions 120 of the strip, engaged with two opposite edges of the sheet and formed to enter said screw-eyes and to bear on the sill.

In testimony whereof I have affixed my signature.

JOSEPH A. MELOON.
